GASEOUS ELECTRIC DISCHARGE DEVICE

Marcello Pirani, Berlin-Wilmersdorf, and Karl Becker, Berlin-Steglitz, Germany, assignors to General Electric Company, a corporation of New York

Application February 10, 1932, Serial No. 592,138
In Germany February 27, 1931

4 Claims. (Cl. 176—122)

The present invention relates to gaseous electric discharge devices generally and more particularly the invention relates to such devices in which the gaseous electric discharge is of the concentrated or so-called "stringy" type.

This type of discharge is produced when the gas or vapor pressure and the current are higher than those used when a diffuse discharge is desired in an electric discharge device. Such a discharge possesses two advantages, first, it is more efficient giving a more intense light emission, and second, since the discharge occupies only a small portion of the cross section of the tube, a glass having a lower melting point and being more easily workable may be used than if the same current were used in an identical device without a "stringy" discharge. This latter advantage has not been obtained in previous devices of this type since the "stringy" gaseous electric discharge column constantly changed its position in the container and often closely approached the container walls to their great injury.

The object of the present invention is to provide an electric discharge device having a "stringy" electric arc discharge in which the container is made of a softer glass than has hitherto been found practical in similar devices having a "stringy" electric arc discharge. Still further objects and advantages attaching to the device and to its use and operation will be apparent to those skilled in the art from the following particular description.

The invention attains its object by providing along the positive column discharge path between the electrodes of a gaseous electric discharge device one or more septums perpendicular to the longitudinal axis of the container of said device, said septum having a diameter which closely approaches the inner diameter of said container and has an opening therein concentric with the longitudinal axis of said container. Said septum or septums guide the "stringy" electric discharge in said container to prevent said discharge from approaching too closely the soft glass walls of said container and thus serve to protect said walls from injury thereby. The septum is supported in the container by any of the methods well known in the art. Said septum is made of a material having a higher melting point than the walls of said container and may be of quartz or of a high melting point metal such as molybdenum, or tungsten. If the septum is of metal it should be thoroughly degassed before the device is placed into operation.

Each of the discharge supporting electrodes

of the device in the preferred embodiment is surrounded by a cylinder made of like materials as said septum and partially closed in the direction of the discharge path to guide the discharge in the region of the electrodes and thus to protect 5 the soft glass walls of the container in that region.

In the drawing accompanying and forming part of this specification two embodiments of the new and novel gaseous electric arc discharge 10 device are shown, in side elevation.

Fig. 1 is a side elevational, partly sectional view of one embodiment of the invention, and

Fig. 2 is a similar view of another embodiment 15 of the invention.

Like numbers denote like parts in both figures.

Referring to Fig. 1 of the drawing the new and novel gaseous electric discharge device comprises a container 1 having a thermionic electrode 2 at each end thereof. Electrode leads 3 of said electrodes 2 are sealed into the pinch parts 4 of stems 5 of said container 1. Said electrodes 2 are of the sintered, mixed metal and oxide type made in accordance with the disclosure of co-pending application, Serial Number 377,044, filed July 9, 25 1929 being the invention of Marcello Pirani and Hans Ewest, or when desired any other suitable type of thermionic electrode may be used. Said electrodes 2 are brought to an electron emitting temperature by an initial glow discharge which 30 rapidly turns into the desired arc discharge, or when desired by a heating filament adapted for that purpose. A septum 6 which, when desired, is of metal such as molybdenum is provided in said container 1 equidistant from the ends of 35 said container 1 and is perpendicular to the longitudinal axis of said container 1. Said septum 6 is supported in said container 1 by flange 8 thereof pressing against the inner wall of said container 1 and the diameter of said septum 6 is 40 co-extensive with the inner diameter of said container 1. An annular opening 7 is provided in said septum 6, and said opening 7 is concentric with the longitudinal axis of the container 1. Each of said electrodes 2 is surrounded by a metal 45 cylinder 9 which is concentric therewith and which has in the direction of the discharge path a flange 10 with an opening 11 therein, and said opening 11 is concentric with the longitudinal axis of the container 1. Said shells 9 are supported by supports 17 sealed in pinch-parts 4 of stems 5.

Said container 1 is greater in diameter in the middle thereof than at its ends to maintain septum 6 in desired position and is filled with an 55

electric discharge conducting gaseous atmosphere at a pressure higher than normal to said device when a diffuse electric discharge is desired to fill the container 1 between said electrodes. When 5 desired the container 1 is 20 cm. in length, 7 cm. in diameter in the middle and 6 cm. in diameter at each end and the gaseous filling comprises a mixture of a rare gas having a low ionizing potential such as argon at a pressure of 5 mm. and 10 a body 12 of vaporizable metal such as mercury in the order of 1 cm.³ is placed in said container 1. In such a device a current of 34 amperes with a potential of 29 volts and 1000 watts applied to the electrodes 2 of the device produces 15 a concentrated, "stringy" electric discharge between said electrodes which is guided by openings 7 and 11 and prevented from changing its position sufficiently from the normal discharge path between said electrodes 2 to injuriously affect the walls of said container, so that a softer glass may be used in the walls of said container 20 1 than in a similar device in which the "stringy" electric discharge is not guided.

When desired, the cylinder 9 surrounding said 25 electrode 2 is connected by a lead 14 having therein resistance 13, to the lead 3 of that electrode 2 to which it is adjacent, as illustrated in dotted lines on the left side of the drawing. This construction creates an electric field about each 30 of the electrodes 2 to decrease the rate of disintegration thereof, and, further, when desired, said cylinder 9 is connected by lead 16, containing a high resistance 15, to the lead 3 of the electrode 2 opposite that electrode 2 to which it 35 is adjacent, as illustrated in dotted lines in the right side of the drawing, said cylinders 9 then serve as auxiliary electrodes during the starting of the device.

It will be understood from the above description 40 that the invention lends itself to a curved type of container in addition to the substantially straight type shown and described in Fig. 1. For example, in the U shaped tube shown in Fig. 2 the electrodes 2 in the container 1 are in the 45 same plane and close to each other and the container 1 is in the shape of two substantially parallel tubes perpendicular to the plane of said electrodes 2 with a curved tube portion connecting said parallel tubes, perforated septums 6, 6', 50 6'' are arranged at the bends or curves in said container 1 along the discharge path in such manner that the "stringy" electric discharge arc path extending from the electrodes 2 to the opening 7 or 7' in the septum 6 or 6', and from the 55 opening 7 or 7' in septum 6 or 6'' to the opening in septum 6' is not invaded by the walls of the container. The electric arc discharge is thus prevented by the perforated guiding septums 6, 6', 6'' from attaching to, or resting on 60 a particular spot on the walls of said container 1 and thus the container walls are protected from injury by the heat of the electric arc discharge between said electrodes 2. A softer, cheaper, and more easily workable glass, therefore, is used as the curved container of an electric discharge device having a "stringy" electric 65

arc discharge than would be practical if the "stringy" electric discharge were not guided and controlled by the means set forth in this invention.

While we have shown and described and have 5 pointed out in the annexed claims certain novel features of the invention, it will be understood that various omissions, substitutions and changes in the forms and details of the device illustrated and in its use and operation may be made by 10 those skilled in the art without departing from the broad spirit and scope of the invention.

What we claim as new and desire to secure by Letters Patent of the United States is:—

1. An electric arc discharge device comprising 15 a container, electrodes sealed therein, a gaseous atmosphere therein under a pressure high enough to support an arc discharge, and a perforated septum separated from said electrodes and mounted along the part of the discharge path 20 between said electrodes occupied by the positive column of an arc discharge, said septum being transverse to the discharge path in said container and guiding an electrical constricted arc discharge in said container away from the walls 25 thereof to prevent destructive action thereby on the main wall of said container.

2. An electric discharge device comprising a 30 container, electrodes sealed therein, a gaseous atmosphere therein, said electrodes being surrounded by a cylinder partially closed in the direction of the discharge path and a perforated septum along the discharge path between said electrodes and separated from said electrodes, said septum being transverse to the discharge path in said container, said septum and said 35 cylinders being adapted to guide the electric discharge in said container away from the walls thereof.

3. An electric discharge device comprising a 40 curved container, electrodes sealed therein, a gaseous atmosphere therein, and a perforated septum along the discharge path between said electrodes, said septum being transverse to the discharge path and located at the bends in said 45 container between said electrodes and adapted to guide the electric discharge in said container away from the walls thereof.

4. An electric discharge device comprising a 50 curved container, electrodes sealed therein, a gaseous atmosphere therein, and a plurality of perforated septums in said container, said electrodes being in the same plane, said container comprising two parallel portions perpendicular to the plane of said electrodes and a curved portion 55 connecting said parallel portions, said perforated septums being arranged along and transverse to the discharge path and at the bends in said container so that the path of the electric discharge extending from electrodes to the opening in the septum and from the opening in one 60 septum to the opening in another septum is not invaded by the walls of said container.
